US0D1053120S

(12) **United States Design Patent** (10) Patent No.: **US D1,053,120 S**
(45) Date of Patent: ** Dec. 3, 2024

(54) **SOLAR PANEL**

(71) Applicant: **BEIJING XIAOMI MOBILE SOFTWARE CO., LTD.**, Beijing (CN)
(72) Inventors: **Tao Wang**, Beijing (CN); **Yuan Gao**, Beijing (CN); **Yong Xu**, Beijing (CN); **Fen Tang**, Beijing (CN)

(**) Term: **15 Years**

(21) Appl. No.: **35/518,039**

(22) Filed: **Feb. 9, 2023**

(80) **Hague Agreement Data**

Int. Filing Date: **Feb. 9, 2023**

Int. Reg. No.: **DM/226861**

Int. Reg. Date: **Feb. 9, 2023**

Int. Reg. Pub. Date: **Aug. 11, 2023**

(30) **Foreign Application Priority Data**

Aug. 18, 2022 (CN) 202230542071.X

(51) **LOC (14) Cl.** **13-02**

(52) **U.S. Cl.**

USPC **D13/102**

(58) **Field of Classification Search**

USPC D10/104.1; D13/101, 102, 103, 107, D13/109, 118, 119, 184, 199; D14/371, D14/432, 439, 441, 447, 451; D21/480, D21/484; D25/109, 140, 144

CPC .. F21S 8/086; F21S 8/088; F21S 9/032; F21S 9/035; H01L 31/042; H01L 31/022425; H01L 31/18

(Continued)

Primary Examiner — Garth Rademaker
Assistant Examiner — Suzanne E Tisdell

(57) **CLAIM**

The ornamental design for a solar panel as shown and described.

DESCRIPTION

- 2.1: Front
- 2.2: Back
- 2.3: Left
- 2.4: Right
- 2.5: Top
- 2.6: Bottom
- 2.7: First Perspective
- 2.8: Second Perspective
- 2.9: First View of state of variation
- 2.10: Second View of state of variation
- 2.11: Third View of state of variation
- 2.12: Fourth View of state of variation
- 2.13: Fifth View of state of variation
- 2.14: Sixth View of state of variation
- 2.15: Seventh View of state of variation
- 2.16: Eighth View of state of variation

1 Claim, 16 Drawing Sheets
